(57) **CLAIM**

The ornamental design for a hugging weighted stuffed toy, as shown and described.

DESCRIPTION

FIG. 1 is a front perspective view of a hugging weighted stuffed toy showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The stipple shading as used in this application is a drafting convention used to show contrast with adjacent surfaces. The cross-hatching pattern sporadically depicted throughout the views is intended to indicate that the pattern is continuous throughout the surface on which the pattern is shown.
